UNITED STATES PATENT OFFICE.

JOHN KNOUS AND ALBERT E. WALLACE, OF HARTFORD, CONN., ASSIGNORS
TO THE POPE MANUFACTURING COMPANY, OF SAME PLACE.

MAKING BICYCLE-FORKS.

SPECIFICATION forming part of Letters Patent No. 313,083, dated March 3, 1885.

Application filed November 28, 1884. (No model.)

To all whom it may concern:

Be it known that we, JOHN KNOUS and ALBERT E. WALLACE, both of Hartford, Connecticut, have jointly invented certain new and useful Improvements in Bicycles, of which the following is a specification.

Our improvements relate more particularly to bicycles of metallic construction, and to that part of the frame of them known as the "rear fork," and our invention consists in a new art or method of making rear forks.

Heretofore rear forks in bicycles of metallic construction, or that part of the metallic frame which, extending from the backbone or perch, connects the latter with the rear or small wheel, have been made either by forging a head or bifurcated stub for connection with the rear end of the perch, and two forks for connecting this head with the rear wheel pin or axle, one to be on either side of the wheel, and welding these forks or extensions to the head; or else by making a rear fork in two pieces, one for each side of the rear wheel, or in two or more pieces, one or two for each side of the wheel, connected with it at the wheel pin or axle, and bolted or riveted to the perch; or by stamping out sheet metal or otherwise constructing of thin semi-tubular metal the two arms or forks, one for each side of the wheel, and having at their lower end additional pieces brazed on to form the lugs for the rear axle, and connecting above in a head or rounded shoulder with a slot in the center, and having another piece of metal to form a stub or tenon for the rear end of the perch inserted in said slot and brazed or otherwise fastened to said head to form a secure connection for the perch.

The peculiar nature and differences of our improvements over the previous methods of construction will be apparent from the following description, taken in connection with the drawings, in which—

Figure 1 shows in side elevation a metal tube. Fig. 2 shows the same modified by the formation of central parts in one step of our process of making it. Fig. 3 shows the same at another stage of the process still more modified. Fig. 4 shows one half of the same in elevation at the next stage in the process. Fig. 5 shows the same after boring and cutting.

Fig. 6 shows the same after removal of superfluous parts and completed shaping as our improved rear fork; and Fig. 7 shows the same article as Fig. 6 in side elevation on a plane at right angles to that of Fig. 6.

55

In constructing our improved fork we take a tube, preferably a small drawn steel tube, of sufficient length to make two of our improved forks, though this is a matter of economy in manufacturing, since each separate fork might be made from a shorter tube in the beginning, and form the middle of it by heating and forging or otherwise to the shape shown in Fig. 2. Having then the two cylinders A' A' connected by a smaller cylinder, B, and 60 having the curved shoulders a a and the sharper shoulders b b, we then draw the cylinders A' A' by means of pony hammers or otherwise to a tapered form, A² A², and having the smaller ends a' a', which have become 65 of considerably thicker metal by the process, the smaller cylindrical part B and the shoulders a a b b remaining the same, we then cut this article, as shown in Fig. 3, transversely in the middle of the smaller cylindrical part B into two similar parts, and each of which in turn is drawn or bent between the shoulder a and the smaller end a' into a curved form, as shown at A³ in Fig. 4. This latter curvature of A³ is made partly as a matter of 70 beauty in the structure of the completed bicycle of which it is to form a part, and partly for practical superiority for strength and elasticity of structure, though a practicable rear fork of substantially our new construction 75 and our improved method might be used with the omission of this curvature. Having the material in the form shown in Fig. 4 or in Fig. 3 divided, we next cut out of the part A² A³ an aperture, c, leaving a suitable arch and proportions and pieces C C, from which side of the tube will be the forked article with the cylindrical head B' and its small shoulder b and larger cylindrical rounded shoulder a, arms A⁴ A⁴, and rear ends, a² a², with proper 80 proportions for strength and appearance. The parts A⁴ A⁴ are then brought, by means of pressure forging or otherwise, to the form and relative position shown in Fig. 6 in rear elevation and in Fig. 7 in side elevation. The ends a² 85

100

a^2 have been flattened and their sides made parallel and their corners rounded in the form shown at $a^4 a^4$. The arms $A^4 A^4$ have been spread and reformed next the parts $a^4 a^4$, 5 so as to leave for strength the nearly semi-tubular shoulders $a^3 a^3$, and now in our improved fork constructed throughout of one homogeneous piece of metal in such proportions and distribution as to be stiff and strong, 10 and of appropriate size and shape, and of extreme lightness. We have the arms $A^5 A^5$, one for either side of the wheel, the lugs $a^4 a^4$, which may be perforated, as at a^5 , for the wheel pin or axle of the small wheel meeting in the 15 strong cylindrical portion a , and the tenon or small cylindrical projection R' and its shoulder b to receive the end of the perch of the bicycle, which may be brazed to it in the usual manner.

We do not here claim the rear fork of improved construction which is the product of this process, as we have set forth and claimed it in another application for a patent thereon.

We claim as new and of our invention—

The described art of producing said bicycle 25 rear fork out of metallic tubing by shaping the tenon B and shoulders a and b thereon, tapering and thickening the opposite end, removing portions of the metal, and shaping to required form, essentially as set forth.

JNO. KNOUS.
ALBERT E. WALLACE.
